UNITED STATES PATENT OFFICE.

WILHELM MAUSS, OF JOHANNESBURG, TRANSVAAL, SOUTH AFRICA

CENTRIFUGAL SEPARATOR.

1,115,852.

Specification of Letters Patent.

Patented Nov. 3, 1914.

Application filed March 25, 1913. Serial No. 756,727.

To all whom it may concern:

Be it known that I, WILHELM MAUSS, a British subject, residing at Commercial Exchange Buildings, Main street, Johannesburg, Transvaal, Union of South Africa, have invented certain new and useful Improvements Relating to Centrifugal Separators, of which the following is a specification.

10 The present invention relates to centrifugal separators for treating ores and the like, of the kind in which the material to be treated is fed into a drum which is rotated about an axis distant from its own axis in order to effect the separation of the constituents of the material and is also rotated at a relatively slow rate about its own axis. The effect of the latter rotation is so to change the position of the surface upon which the separated material of higher specific gravity is deposited as to diminish or reverse the effect of the centrifugal force in holding the deposited material on the surface of the drum and thus enable such material to be readily separated therefrom. 25 The apparatus usually consists of vessels symmetrically disposed about the main axis of rotation.

The purpose of the present invention is 30 to improve the removal from the drum of the material deposited on the wall thereof.

In the accompanying drawing is shown apparatus embodying the present improvements, Figure I being a general elevation, 25 partly in section, and Fig. II a section on the plane A—B, Fig. I.

1 is a main shaft rotated about its axis 2 by suitable driving means 3, 4 and having rigidly secured to it a cradle 5. Said cradle 40 carries two oppositely disposed drums 6 having their axes 7 spaced from axis 2 so that upon rotation of shaft 1 they are whirled bodily around the same. The drums shown are conical below and are provided 45 with an overflow lip *a* at the top, while their axes 7 are so inclined upwardly and outwardly that the portion 10 of the wall remote from axis 2 forms with the overflow lip *9* a separating chamber 11, and so also 50 that the portion 12 of the wall next to axis 2 is vertical. Each drum is mounted in the cradle 5 to be rotatable about its own axis 7 and is so rotated by means of gearing 13, shaft 14 passing through shaft 1, pinion 15 55 thereon and the annular racks 16 on the outside of the drums. Shaft 1 is bifurcated

at 17 to permit the engagement of said pinion 15 with the racks 16. Each drum is served by a feed pipe 18 extending from a common trough 19 mounted upon and rotating with shaft 1.

In the operation of such apparatus, upon the mixed material—which may be supposed to be ore pulp and cyanid solution—being fed in through pipes 18, it forms a wall 20, 21 in the separating chambers 11. The liquid segregates as an inner layer 20 and flows away over lip *9* into receiver 22, while the ore 21 deposits upon the wall of the drum and tends to adhere firmly thereto. The deposited pulp is carried around with the drum as the latter rotates on its axis 7 (in the direction of the arrow, Fig. II), thus causing the pulp to emerge from the layer of liquid and at the same time progressively reversing the relative positions of said pulp and said surface in regard to the main axis of rotation 2. The effect of the centrifugal force in holding the pulp to the surface of the drum is thus gradually diminished and even reversed after the surface passes the position in which it is radial to axis 2.

In former apparatus of this kind the reversal of the effect of the centrifugal force has been utilized to throw the deposited material from off the surface of the drum preparatory to its discharge from the apparatus. It is, however, considered that dependence upon such centrifugal detachment is undesirable. Materials which pack closely require very considerable force to detach them and accordingly tend to break off irregularly and to fly back into the separating zone. They may also fail to detach altogether, and in either case the balance of the apparatus is dangerously disturbed.

According to this invention the centrifugal detachment of the ore is prevented as far as possible, and it is sought only to bring the deposited ore into a substantially neutral zone in reference to the centrifugal force, so that its removal is rendered easy, and then to detach it mechanically. To this end, the inner wall of the drum is brought as closely as possible to the axis 2 and a plow 23 is provided to remove or insure the removal of the material. The plow is fixed relatively to axis 2 and is of suitable form according to the material to be dealt with. Thus, it may be a simple blade, as shown, or in the case of very hard or tough material,

2
a series of disk plows may be preferable. Material detached by the plow falls into the bin 24. By thus retaining the settled material on the drums until it reaches fixed 5 points and then completely removing it therefrom at such points, the balance of the apparatus is much improved.

25 is an annular launder which is disposed below the path of the outer walls of 10 the drums. In the event of the apparatus stopping or slowing down to substantially below its normal speed, the unseparated material falls out into said launder 25 and is thus prevented from mingling with the 15 separated product in bin 24. This feature is of especial value in such cases as the separation of gold-bearing solution from cyanided ores, in preventing the loss of valuable material. A pump 26 and con- 20 nections 27 are shown, by which the unseparated materials thus caught may be returned to their source 28.

As a further precaution against loss or imperfect separation, the supply of unsep-

arated material to the separator may be controlled by means which automatically cuts off the supply when the speed of the separator falls below a fixed limit. A simple form of such means consists of a governor 29 on the main shaft 1 which is arranged to 30 trip a trigger 30 and allow the gate 31 to fall, so closing the outlet from the source 28.

What I claim and desire to secure by Letters Patent is:—

35 Centrifugal separating apparatus comprising a drum rotatable about its own axis and also about an external axis, said drum being very close to said external axis, and a plow fixed relatively to and near to the main axis for positively detaching deposited 40 material from the surface of the drum.

In testimony whereof I affix my signature in presence of two witnesses.

WILHELM MAUSS.
